COIN CONTROLLED MECHANISM

Louis H. Morin, Bronx, N. Y., assignor to Pack-Morin, Inc., New York, N. Y., a corporation of New York

Application November 18, 1933, Serial No. 698,598

22 Claims. (Cl. 194—55)

This invention relates to coin controlled mechanisms such as are commonly employed in vending machines.

The primary object of the present invention is to generally improve coin controlled mechanisms such as are used in slot machines or automatic vending machines for the sale of a variety of articles, for example, candy, handkerchiefs, sanitary napkins, and so forth. A further object of my invention resides in the provision of a coin controlled mechanism which will accurately distinguish true coins from spurious coins, and which will not respond to the latter regardless of whether ferrous or non-ferrous, solid or washer-shaped, cardboard, sheet metal, or over-size or under-size as to diameter or thickness.

A more particular object of my invention is to avoid using the coin as a load transmitting element, and to instead employ the same simply to trigger and indirectly make effective a separate and independent load transmitting mechanism. With this arrangement the mechanism may, on the one hand, be designed for severe loads, and, on the other hand, may treat and handle the coin in a relatively gentle manner, making the detection of spurious coins more sensitive. Still another object of my invention is to provide trigger mechanism which must not only be actuated by a coin of accurate dimension, but which must be operated in proper time relation to the parts of the associated mechanism, so that delay or mis-timing in the release of the trigger mechanism will itself prevent operation.

Another object of my invention is to prevent actuation of the trigger mechanism by inserting a wire or pick through the coin slot; and with this object in view I provide a trigger lock for preventing movement of the trigger, this trigger lock being released by movement of a proper coin in the mechanism toward the trigger. Still another object of my invention centers about the stroke completion means intended to prevent the coin or/and coin carriage from being moved back after only partial operation. Such stroke completion means, if always effective, may result in the mechanism being left in intermediate position by an idler casually playing with the operating handle. In accordance with a further feature and object of my invention, the stroke completion means is made ineffective except upon deposit and movement of a coin in the mechanism.

The delivery mechanism associated with the coin controlled mechanism for actually delivering goods to the purchaser may be of a type movable for successive deliveries by simply shaking the

entire box or casing of the apparatus. One object of my invention resides in the provision of mechanism, specifically in the form of a normally engaged holding pawl or detent for preventing movement of the delivery system except through operation of the coin controlled mechanism. During a part of the operating cycle of the coin controlled mechanism the detent is of necessity released or disengaged. It may thus become possible for a person to deposit a proper coin in the mechanism and to operate the same to only that point where the detent is disengaged, and to thereupon shake the casing in an endeavor to obtain a series of deliveries instead of only one delivery for the single coin. A further object of my invention is to prevent this possibility, and to this end I provide an additional safety stop which moves into stop relation with the mechanism when the detent is disengaged.

To the accomplishment of the foregoing and such other objects as will hereinafter appear, my invention consists in the coin controlled mechanism and the elements thereof and their relation one to the other, as hereinafter are more particularly described in the specification and sought to be defined in the claims. The specification is accompanied by drawings in which:

Fig. 1 is a front elevation of one form of coin controlled mechanism embodying features of my invention;

Fig. 2 is a section taken in elevation in the plane of the line 2—2 of Fig. 1;

Fig. 3 is a longitudinal section taken in the plane of the line 3—3 of Fig. 2;

Fig. 4 is an end elevation of a part of the mechanism;

Fig. 5 is a horizontal section taken in the plane of the line 5—5 of Fig. 3;

Fig. 6 is a fragmentary section similar to Fig. 3 and showing the disposal of a ferrous slug;

Fig. 7 is explanatory of the detection and disposal of a washer, a cardboard, or a thin slug;

Fig. 8 is a partially sectioned rear elevation taken in the plane of the line 8—8 of Fig. 2;

Fig. 9 is a rear elevation;

Fig. 10 is a section generally similar to Fig. 3 but showing a modified form of my invention;

Fig. 11 is a horizontal section taken in the plane of the line 11—11 of Fig. 10;

Fig. 12 is a rear elevation of the modified form of the invention; and

Fig. 13 is a section taken in the plane of the line 13—13 in Fig. 12.

Referring to the drawings, one form of my invention is shown in Figs. 1 to 9, and a second

form in Figs. 10 to 13. The coin controlled mechanism as shown does not include the coin receptacle nor the vending or dispensing apparatus responsive to the coin mechanism, for these may be of conventional type. In both forms of the invention the coin mechanism includes a front plate or escutcheon 12 adapted to be exposed on the vending machine and carrying a coin slot 14 and an operating handle 16, best shown in Figs. 1 and 2 of the drawings. The coin mechanism terminates with a driven gear 18 located at the back of the coin mechanism and best shown in Figs. 2, 9 and 12 of the drawings. It will be understood that an appropriate part of the vending machine mechanism is suitably geared to the gear 18, so that rotation of gear 18 results in the delivery or release of the article being sold.

As is usual with these devices, a coin is deposited by the customer in coin slot 14, and the handle 16 is thereupon operated, and it is the function of the coin mechanism to produce movement of the gear 18 in response to movement of the operating handle 16 if a true coin of proper dimension has been deposited in the coin slot, but to prevent movement of gear 18 if no coin or a spurious coin is deposited in the coin slot.

Referring now to Figs. 1 through 6 of the drawings, the handle 16 is secured to a pinion 20 meshing with a rack 22 formed at the bottom of a longitudinally reciprocable coin carriage 24. The coin carriage is normally urged to the left, as viewed in Figs. 1 and 3, by a spring 26 tensioned between the carriage at 28 and the stationary frame at 30. Spring 26 restores the coin carriage to initial position, thereby placing the coin seat or recess 32 on the carriage in alignment with coin slot 14. At the same time the operating handle 16 is, of course, raised to the starting position shown in Fig. 1.

When a true coin of proper dimension is deposited in slot 14, it rests on the coin carriage in a manner shown by coin 34 in Figs. 3 and 4, and movement of handle 16 thereupon causes the coin carriage with the coin to move toward the right, as viewed in Fig. 3. In the course of its movement, and preferably near the beginning thereof, the top edge of coin 34 bears against a trigger 36 disposed in its path and causes the same to swing outwardly.

The trigger mechanism further includes a shaft 38 and a stop finger 40, the stop finger 40 and the trigger 36 both being fixedly secured to shaft 38 for simultaneous movement, as shown in Fig. 4.

Referring now to Figs. 8 and 9, the lower end of stop finger 40 bears against the arm 42 of a first pawl 44, the pawl 44 being pivoted at 46 on an oscillatable pawl plate 48. Pawl 44 is normally urged in a clockwise direction into engagement with a single toothed wheel 50 by a spring 52, but is restrained against movement by trigger finger 40. This in turn is normally drawn to stop position by a spring 54 tensioned between stop finger 40, at the point 56, and a screw 58 on the stationary frame of the coin mechanism, the stop position being determined by a fixed abutment 60.

The single toothed wheel 50 is mounted on an extension or hub 62 formed integrally with pinion 20, and is keyed to pinion 20 by a key indicated at 64 in Fig. 2. Pawl plate 48 is oscillatable on extension 62. It will thus be evident that upon movement of trigger 36 outwardly by coin 34, the stop finger 40 is moved out of the way of pawl arm 42, permitting pawl 44 to engage the tooth

of wheel 50. The continued rotation of wheel 50 with pinion 20 causes a counter-clockwise rotation of pawl plate 48, as viewed in Figs. 8 and 9.

Pawl plate 48 in turn carries a driving pawl 5 or second pawl 66 pivoted at 68 and cooperating with a ratchet 70, the pawl being urged into engagement with the ratchet by a spring 72. The ratchet 70 is, in the present case, provided with four teeth, it being contemplated that the vending machine be operated in response to a quarter of a revolution of the main driven gear 18. Ratchet 70 is preferably formed integrally with gear 18, as is best shown in Fig. 2. Gear 18 is preferably further formed integrally with an additional 15 ratchet wheel 74, the teeth of ratchet 74 being faced opposite those of ratchet 70. Ratchet 74 functions as a holding ratchet and cooperates with a detent 76 best shown in Fig. 9, this detent preferably being formed integrally with the stop 20 finger 40. It will thus be evident that actuation of the trigger mechanism by the coin releases detent 76 to permit rotation of gear 18, and releases pawl 44 to produce the desired rotation of gear 18.

The rotation of gear 18 is produced and accompanied by an oscillation of pawl plate 48. This pawl plate is restored to initial position by a spring 78 anchored at one end by stationary screw 80 and at its opposite end on pawl plate 48 by means of a pin 82. The initial position of the pawl plate is determined by an abutment or stop 84 formed on the frame of the coin mechanism.

During the continued movement of the operating handle 16, the coin carriage 24 is, of course, moved further to the right, as viewed in Fig. 3. During this continued movement the coin passes over a coin ratchet 90 pivoted at 92 and normally held in elevated position by a spring 94. This ratchet necessitates completion of the operating stroke of the handle, for otherwise the coin is restrained against return movement by the ratchet. When the operating stroke has been completed, the coin is moved past the end of coin ratchet 90 and is thereupon released and permitted to fall downwardly into an appropriate coin receptacle via sloping track or guide 96, the coin receptacle being, in the usual case, positioned to the right and below the coin mechanism, as viewed in Fig. 3.

As so far described, it has been assumed that the coin deposited in the coin mechanism is a true coin of proper dimension. Further features of the present mechanism may best be described with reference to attempted misuse of the machine. If the coin is over-sized as to diameter or thickness, it will not pass through the coin slot 14, and consequently cannot be employed. If the coin is under-size as to diameter, it will simply pass beneath the trigger 36 without operating the trigger. If the coin is undersize as to thickness, it will recline rearwardly in the manner indicated by the slug 100 shown in Fig. 7, for the coin is supported at its lower edge in the seat or recess 32 and is further supported by only the pin 102 the tip of which is accurately located to hold a coin of proper thickness in an erect position. It will be evident from inspection of Fig. 7, that the slug 100 will not bear against the trigger 36 until the coin carriage 24 is moved to the right a distance indicated by the spacing at the top of the figure. This is to be contrasted with the case of a true coin which, in the position shown in Fig. 7, would already be in contact with 75

the trigger 36. There consequently is a lag or delay in the movement of the trigger, and this delay is taken advantage of to prevent effective coupling between the operating handle 16 and the driven gear or end gear 18. Referring to Fig. 8, the relative spacing and location of the stop finger 40, the pawl 44, and the single tooth of driving wheel 50, are so determined that with a true coin the pawl 44 engages the tooth 50 with but little clearance. When the trigger release is delayed, the pawl 44 is freed just after passage of the notch or tooth in wheel 50, and the subsequent continued rotation of driving wheel 50 is ineffective to move pawl 44 or pawl plate 48. Consequently a coin under-size as to thickness, like a coin under-size as to diameter, does not succeed in coupling or clutching the operating handle 16 to the driven gear 18.

If a ferrous or magnetic slug is inserted in the machine, it is disposed of by a magnet 104, best shown in Figs. 3, 4 and 6. The magnet is U-shaped, and its open end is disposed over the coin. Its closed end 106 is pivotally mounted on the frame between bearings 108 and 110. The magnet is normally held downwardly upon a stationary rest 112, forming a part of the frame, by a spring 114.

At the beginning of the operating stroke of the handle 16, the magnet 104 is elevated from the position shown in Fig. 3 to the position shown in Fig. 6, so that if the slug 34' is made of ferrous metal, it is drawn upwardly in the manner shown in Fig. 6. This releases the lower edge of the coin from the seat 32 on coin carriage 24, and continued movement of the coin carriage simply brushes the coin from the magnet.

The upward movement of the magnet is obtained by mechanism best shown in Fig. 8. The single toothed wheel or driving ratchet 50 is cut away as shown at 116 to form a cam surface in which rests the cam follower portion 118 of a lever 120 pivoted at 122. The upper end of the lever is bent at right angles to form a finger 124 which passes through a slot 126 and lies beneath the magnet 104. The relation of the finger 124 to the magnet 104 will also be clear from inspection of Figs. 3 and 6. It will be manifest that the initial rotation of wheel 50 with the operating handle 16 elevates lever 120 which in turn elevates the magnet 104.

If the slug inserted in the machine is provided with a hole in the center, as is the case with a washer or a token, the slug falls back over the supporting pin 102, as is clearly illustrated by the washer-like slug 130 in Fig. 7. In this position the upper edge of the slug is far below trigger 36 and is incapable of tripping the same.

If the slug inserted in the machine is flexible, as is the case with cardboard, it will bend or yield about the supporting pin 102, as is illustrated by the slug 132 in Fig. 7, and will overcome the resistance of trigger 36, if at all, too late to cause engagement of the pawl and single toothed ratchet.

Return movement of the coin is prevented not only by the coin ratchet 90 and trigger 36 but also by a catch or stop 134 best shown in Fig. 5. This catch is formed at one end of an arm 136 pivoted at 138 and urged to the normal position shown in Fig. 5 by a compression spring 140. The stop finger 134 passes through a slot 142 cut in the frame plate, and the location of the stop finger will be evident from an inspection of Figs. 3, 4, and 6.

To prevent damage to the coin mechanism by

extremely forceful operation of handle 16 in the event of the mechanism becoming internally jammed, I provide a safety clutch or coupling between the handle 16 and the pinion 20. For this purpose the hub 144 of the handle (see Fig. 2) is keyed to a washer 146 provided with a pair of diametrically opposed teeth or bumps 148 which engage in mating recesses formed in the end face of hub 150 of pinion 20. The handle and pinion are held tightly together in the mating or nested relation shown in Fig. 2, by a bolt 152 the head end of which bears against a compression spring 154 housed within the hub of the handle. It will thus be evident that upon excessive resistance to rotation of the handle, the handle will move outwardly against the resistance of spring 154, permitting the teeth or bumps 148 to ride out of the mating recesses on pinion 20.

A modified form of my invention is shown in Figs. 10 through 13, and will next be described. One important respect in which the second form of the invention differs from the first resides in the provision of means to lock the trigger 36 against improper movement, as, for example, by a wire or pick inserted through the coin slot and manipulated in an effort to move the trigger. For this purpose I provide a trigger lock 160, best shown in Figs. 11 and 12, which is disposed directly in front of the depending arm 240 mounted on the bearing shaft 38 of trigger 36. Trigger lock 160 forms an integral part of a lever 162 pivoted at 164 and normally urged inwardly to the position shown in Fig. 11 by a compression spring 166. The innermost part 168 of lever 162 passes through a slot 170 in the rear wall 172 of the coin mechanism. This part of the apparatus is largely analogous to the coin stop 134 mentioned when describing the first form of the invention, but in the present case the part 168 is greatly elongated to be effective during nearly all of the stroke of the coin and is tapered to act as a coin follower along which the coin on the coin carriage wipes during its movement and by which the lever 162 is moved outwardly against the resistance of spring 166. When coin follower 168 is moved outwardly by the coin to lie flush with wall 172 of the mechanism, the trigger lock 160 is moved out of the path of arm 240, thus permitting the latter to be tripped by the coin when the coin reaches the trigger.

The present modification of the invention also differs from that first described in completely eliminating the coin ratchet. The latter, while simple and effective for most purposes, is apt to become clogged and troublesome in the event of someone dropping a paper clip or the like into the coin slot. In the present form of the invention, as will be manifest from an inspection of Figs. 10 and 11, the coin carriage 224 terminates at the coin seat 232, and has no ratchet associated therewith, so that objects dropped in the coin slot fall readily from the coin carriage down chute 96 into the coin receptacle. In fact, most undersized slugs and improper objects fall from the coin carriage immediately upon deposit without any movement of the coin carriage and without necessitating the assistance of coin follower 168 or/and trigger 136.

In the present arrangement completion of the stroke of the coin carriage is insured by pawl and ratchet mechanism including a ratchet 174 (see Fig. 11) formed on the side of coin carriage 224 near the end thereof, and cooperating with a pawl or detent 176 movable through a slot 178 in wall 172 under the influence of a relatively light com-

pression spring 180, detent 176 being pivoted at 182. While it is important to lock the coin carriage against return movement when a coin is placed therein, it is actually undesirable to thus 5 lock the same when no coin has been placed therein, for otherwise an idle bystander may move the operating handle to an intermediate position and there leave the same, thus blocking insertion of a coin by a following purchaser attempting to use 10 the mechanism. To avoid this difficulty I interconnect the trigger lock mechanism with the stroke completion mechanism; and, specifically, I extend the lever 162 rearwardly to form a stop finger 184 which normally bears against a stop pin 186 formed on detent 176 (see Figs. 11 and 12). As will be evident in Fig. 11, the detent 176 is 15 normally held out of engagement with ratchet 174, making the stroke completion means normally ineffective. Upon insertion of a coin, however, movement of the coin carriage forces the 20 coin follower 168 outwardly and thereby releases detent 176 for engagement with ratchet 174, thus preventing return movement of the coin carriage until its stroke is completed, at which time the 25 coin passes coin follower 168 which immediately moves inwardly and thus again disengages detent 176.

It has already been explained in connection with the first form of the invention that unintended movement of gear 18 is prevented by an appropriate holding pawl and ratchet mechanism, this mechanism being specifically exemplified by ratchet 74 and detent 76, the latter being formed integrally with lever or stop finger 48. The present embodiment of the invention is similarly provided with a lock wheel or ratchet 274 with which mates a holding pawl or detent 276, the latter preferably being formed integrally with lever 240 (see Fig. 12). In the present case the wheel 274 30 differs slightly in providing a positive lock against movement in either direction, instead of merely locking gear 18 against movement in one direction. This precaution is desirable when the delivery mechanism geared to the coin mechanism 35 is susceptible of being operated in either direction, as by violently shaking the casing of the vending machine.

With such a delivery mechanism it may become possible for a purchaser to insert a proper coin 50 and to only partially operate the handle or lever until the detent 76 or 276 is released, and to thereupon violently shake the vending machine while holding the operating handle against movement, in an effort to cause successive or continued delivery by the delivery mechanism, all in 55 response to the insertion of only a single coin.

To prevent this possibility I provide an additional safety stop for limiting the rotation of the gear 18 (or related mechanism), said safety stop 60 preferably being effective when the detent is disengaged. Referring to Figs. 11, 12 and 13 of the drawings, the safety stop in the present instance takes the form of a reciprocable stop pin 190 movable toward and into stop relation with lugs or 65 projections 192 formed on the inner face of gear 18. Four such stop lugs or projections 192 are provided because in the present case gear 18 is designed for quadrant movement for each operation. The stop pin 190 is normally urged away 70 from gear 18 by a compression spring 194 housed within a bushing 196 forming a part of or cast integrally with the back plate 172 of the mechanism. Spring 194 bears at one end against an enlarged head 198 on the stop pin, which in turn 75 carries a cam follower pin 200 the upper end of

which bears against a camming surface 202 formed on one side of the coin carriage near the lower edge thereof, as is best shown in Figs. 11 and 13.

It will be noted from inspection of Fig. 11 that during the first part of the movement of the coin carriage, the safety stop pin 190 is forced into stop position, thus preventing completion of even a quarter turn of gear 18. It is during this part of the movement of the coin carriage that the holding detent 276 is disengaged in response to movement of the coin trigger 36. Near the end of the movement of the coin carriage, the cam track or surface 202 is cut away, as is clearly shown in Fig. 11, thus permitting the safety stop pin 15 190 to move away from gear 18 so that the gear may complete the desired quarter turn in response to movement of the operating handle. It is important to note, however, that the arrangement of the parts is such that during this last fraction of movement of the coin carriage the trigger 36 has already been released and holding detent 276 has already been moved back against the periphery of wheel 274. During the continued movement of gear 18 the wheel 274 moves past 25 detent 276, and at the completion of a quarter turn the detent automatically moves into the approaching notch on wheel 274, thus anchoring gear 18 against the possibility of further movement. There is consequently no point at which 30 gear 18 is free for continuous movement, because the safety stop is not disengaged until the holding pawl or detent has already been freed for active engagement.

The present form of the invention also differs 35 in the arrangement used for elevating the magnet 104. Referring to Figs. 10 and 11 of the drawings, the coin carriage 224 is provided on its upper side with a camming projection 204 which is generally triangular in outline and which is 40 so disposed as to bear against a part of the magnet, specifically the cross bar or sleeve 206. It is evident that the initial movement of the coin carriage causes cam 204 to bear against sleeve 206 and to thereby elevate the magnet 104, thus unseating and discarding ferrous slugs. This magnet elevating mechanism may, of course, be employed in the first form of coin mechanism also, but is especially convenient in the present coin mechanism in order to avoid interference with 45 the stroke completion means and safety stop means.

With respect to both forms of the invention I 50 may briefly point out that the device 210, pivoted on the rear wall of the mechanism, is simply an "empty stop" which moves into the path of the coin carriage and prevents the coin carriage from returning to its initial position should the vending machine be emptied of its wares. Incomplete return of the coin carriage prevents insertion of 55 a coin. I may also mention, in passing, that the bearing 212, forming a part of the rear plate 172 of the mechanism, is simply intended to receive a shaft carrying a gear which meshes with gear 18 and which forms a part of the delivery mechanism to which the present coin controlled mechanism is connected in a particular instance. The connection of the delivery mechanism to gear 18, or to any appropriate driven element corresponding to gear 18, may, of course, be varied as desired, in accordance with the requirements of 60 the particular vending machine in which the coin mechanism is employed.

It is believed that the mode of constructing and 65 using, as well as the many advantages of my im- 70 75

proved coin mechanism, will be apparent from the foregoing detailed description thereof. With a true coin of proper dimension, the coin is not used as a direct driving element for the transmission of force, but rather is simply employed to trip trigger mechanism, which in turn controls the coupling of the operating handle to the driven gear. This coupling mechanism may be made rugged and capable of transmitting considerable force between the operating handle and the driven gear. The coin is itself subjected to no mutilation. Spurious coins are ineffective to operate the mechanism, and the mechanism is sensitive to slugs under-size as to thickness, as well as to slugs under-size as to diameter. Ferrous slugs, washers, flexible slugs, and the like, are all rejected by the mechanism.

The use of a trigger facilitates the detection of slugs, and in the present mechanism a time factor is introduced, necessitating operation of the trigger at exactly the right instant. In fact, the mechanism may, if desired, be adjusted to such hairline sensitivity that even a slightly thin but otherwise proper coin will be ineffective to operate the mechanism, and this degree of sensitivity should ordinarily be avoided. In addition to the necessity for operating the trigger at the right instant, the trigger may further be provided with a lock, making it impossible to operate the trigger by a wire or pick inserted through the coin slot, this trigger lock being released only upon movement of a coin along a coin follower. The mechanism may be provided with stroke completion means with or without using the coin for this purpose, and the stroke completion means is ineffective in the absence of a coin. The delivery mechanism may be provided with holding pawl or detent mechanism, and additionally provided with a safety stop operative when the detent is disengaged and insuring against any possibility of shaking or otherwise moving the delivery mechanism through more than a single delivery cycle upon deposit of one coin.

It will be apparent that while I have shown and described my improved coin controlled mechanism in preferred forms, many changes and modifications may be made in the structures disclosed, without departing from the spirit of the invention, defined in the following claims.

I claim:

1. Coin controlled mechanism comprising a manually oscillatable driving member, an elongated coin carriage longitudinally reciprocated thereby, a driven member rotatable coaxially with said driving member, coupling means for positively coupling the driven member to the manually operable member, and intermediate trigger means responsive to movement of a coin on the coin carriage for making the aforesaid coupling means effective.

2. Coin controlled mechanism comprising a manually oscillatable driving member, an elongated coin carriage longitudinally reciprocated thereby, a driven member rotatable coaxially with said driving member, coupling means for positively coupling the driven member to the manually operable member, intermediate trigger means responsive to movement of a coin on the coin carriage for making the aforesaid coupling means effective, said trigger means being so disposed relative to the coin carriage that an undersized slug is incapable of operating the trigger means.

3. Coin controlled mechanism comprising a manually operable member, a coin carriage moved thereby, means to guide a deposited coin directly

to the coin carriage, a driven member, means for coupling the driven member to the manually operable member, intermediate trigger means responsive to movement of a coin on the coin carriage for making the aforesaid coupling means effective, and magnetic means to make a ferrous slug deposited on said coin carriage ineffective to trip the trigger means, said means including a movable magnet disposed immediately adjacent the coin when the coin carriage is in coin receiving position, and means to move the magnet away from the carriage upon movement of the carriage.

4. Coin controlled mechanism comprising a manually operable member, a coin carriage moved thereby, means to guide a deposited coin directly to the coin carriage, a driven member, means for coupling the driven member to the manually operable member, intermediate trigger means responsive to movement of a coin on the coin carriage for making the aforesaid coupling means effective, means to make a washer-like slug deposited on said coin carriage ineffective to trip the trigger means, and means to cause delivery of said slug from the coin carriage to prevent re-use of the slug.

5. Coin controlled mechanism comprising a manually oscillatable driving member, an elongated coin carriage longitudinally reciprocated in response to oscillation of said member, a driven element rotatable coaxially with said driving member, pawl and ratchet mechanism for coupling said driven element to the driving member, and trigger means mechanically responsive to movement of a coin in the carriage for releasing the pawl for engagement with the ratchet and thereby making the coupling means effective.

6. Coin controlled mechanism comprising a manually operable driving member, an elongated coin carriage longitudinally reciprocated in response to rotation of said member, a coin seat thereon for receiving and supporting a coin for broadside movement, a driven element, pawl and ratchet mechanism for coupling said driven element to the driving member, and trigger means responsive to broadside movement of a coin in the carriage for causing engagement of the pawl and thereby making the coupling means effective, the disposition of the parts being such that a slug of insufficient thickness delays operation of the trigger mechanism and is ineffective to couple the driven element to the driving member.

7. Coin controlled mechanism comprising a manually operable driving member, a coin carriage moved in response to rotation of said member, a driven element, a pawl and a single toothed ratchet mechanism for coupling said driven element to the driving member, and trigger means responsive to movement of a coin in the carriage for releasing the pawl for engagement with the ratchet tooth and thereby making the coupling effective, the disposition of the parts being such that delayed operation of the trigger mechanism releases the pawl too late for engagement with the tooth, and means on said coin carriage to support an undersized or apertured spurious coin that the trigger is tripped late.

8. Coin controlled mechanism comprising a manually operable driving member, an elongated coin carriage longitudinally reciprocated in response to rotation of said member, a driven element, driving pawl and ratchet mechanism for coupling said driven element to the driving member, holding pawl and ratchet mechanism for normally holding the driven element against

movement, and trigger means responsive to movement of a coin in the carriage for causing engagement of the driving pawl and disengagement of the holding pawl and thereby making the coupling means effective.

9. Coin controlled mechanism comprising a manually operable driving member, a coin carriage moved in response to rotation of said member, a driven element, a pawl plate, a first pawl and a single toothed ratchet mechanism for coupling said pawl plate to the shaft, a second pawl and a multiple toothed ratchet for coupling said pawl plate to the driven element, trigger means responsive to movement of a coin in the carriage for causing engagement of the first pawl and thereby making the coupling means effective, and means causing restoration of the driving member and the pawl plate to initial position.

10. Coin controlled mechanism comprising a manually operable member, a coin carriage moved thereby, a driven member, means for coupling the driven member to the manually operable member, intermediate trigger means responsive to movement of a coin on the coin carriage for making the aforesaid coupling means effective, a trigger lock normally preventing actuation of the trigger, and means responsive to a coin on the coin carriage for releasing the trigger lock.

11. Coin controlled mechanism comprising a manually operable member, an elongated coin carriage longitudinally reciprocated thereby, a driven member, means for coupling the driven member to the manually operable member, intermediate trigger means responsive to movement of a coin on the coin carriage for making the aforesaid coupling means effective, a trigger lock normally preventing actuation of the trigger, and a coin follower having an elongated bearing surface lying in the path of movement of a coin in the coin carriage for releasing the trigger lock in response to movement of a coin by the coin carriage toward the trigger.

12. Coin controlled mechanism comprising a manually operable member, a coin carriage moved thereby, a driven member, means for coupling the driven member to the manually operable member, intermediate trigger means responsive to movement of a coin on the carriage for making the aforesaid coupling means effective, normally ineffective stroke completion means for preventing return movement of the carriage until it has completed its operating stroke, and means responsive to a coin on the coin carriage for making said stroke completion means effective.

13. Coin controlled mechanism comprising a manually operable member, a coin carriage moved thereby, a driven member, means for coupling the driven member to the manually operable member, intermediate trigger means responsive to movement of a coin on the carriage for making the aforesaid coupling means effective, pawl and ratchet stroke completion means to prevent return movement of the carriage until it has completed its operating stroke, and coin follower means normally disengaging said pawl and ratchet but responsive to movement of a coin by the coin carriage for engaging said pawl and ratchet.

14. Coin controlled mechanism comprising a manually operable driving member, a coin carriage moved in response to rotation of said member, a driven element, holding pawl and ratchet mechanism for normally holding the driven element against movement, means responsive to movement of a coin in the carriage for causing

disengagement of the holding pawl and movement of the driven element, and a safety stop movable into stop relation with the driven element when the holding pawl is disengaged for limiting the movement of the driven element during disengagement of the holding pawl.

15. Coin controlled mechanism comprising a manually operable driving member, a coin carriage moved in response to rotation of said member, a driven element, driving pawl and ratchet mechanism for coupling said driven element to the driving member, holding pawl and ratchet mechanism for normally holding the driven element against movement, trigger means responsive to movement of a coin in the carriage for causing engagement of the driving pawl and disengagement of the holding pawl and thereby making the coupling effective, and a safety stop for limiting the movement of the driven element during the disengagement of the holding pawl.

16. Coin controlled mechanism comprising a manually operable driving member, a coin carriage moved in response to rotation of said member, a driven element, driving pawl and ratchet mechanism for coupling said driven element to the driving member, holding pawl and ratchet mechanism for normally holding the driven element against movement, trigger means responsive to movement of a coin in the carriage for causing engagement of the driving pawl and disengagement of the holding pawl and thereby making the coupling effective, a safety stop movable into or out of stop relation with the driven element when the holding pawl is disengaged for limiting the movement of the driven element during one disengagement of the holding pawl, and means on said coin carriage for controlling the movement of said safety stop in response to movement of the coin carriage.

17. Coin control mechanism comprising a manually operable member, a coin carriage moved thereby, a driven member, means for coupling the driven member to the manually operable member, intermediate trigger means responsive to movement of a coin on the carriage for making the aforesaid coupling means effective, a trigger lock normally preventing actuation of the trigger, normally ineffective stroke completion means for preventing return movement of the carriage until it has completed its operating stroke, and means for releasing the trigger lock and for making said stroke completion means effective in response to a coin on the coin carriage.

18. Coin control mechanism comprising a manually operable member, an elongated coin carriage longitudinally reciprocated thereby, a driven member, means for coupling the driven member to the manually operable member, intermediate trigger means responsive to movement of a coin on the carriage for making the aforesaid coupling means effective, a trigger lock normally preventing actuation of the trigger, normally ineffective stroke completion means for preventing return movement of the carriage until it has completed its operating stroke, and a coin follower having an elongated bearing surface lying in the path of movement of a coin in the coin carriage for releasing the trigger lock and for making said stroke completion means effective in response to movement of a coin on the coin carriage toward the trigger.

19. Coin controlled mechanism comprising a manually operable driving member, a coin carriage moved in response to rotation of said member, a driven element, driving pawl and ratchet

mechanism for coupling said driven element to the driving member, holding pawl and ratchet mechanism for normally holding the driven element against movement, trigger means responsive to movement of a coin in the carriage for causing engagement of the driving pawl and disengagement of the holding pawl and thereby making the coupling effective, a trigger lock normally preventing actuation of the trigger, normally ineffective stroke completion means for preventing return movement of the carriage until it has completed its stroke, and coin follower means for releasing the trigger lock and for making the stroke completion means effective in response to a coin on the coin carriage.

20. Coin controlled mechanism comprising a manually operable driving member, a coin carriage moved in response to rotation of said member, a driven element, driving pawl and ratchet mechanism for coupling said driven element to the driving member, holding pawl and ratchet mechanism for normally holding the driven element against the movement, trigger means responsive to movement of a coin in the carriage for causing engagement of the driving pawl and disengagement of the holding pawl and thereby making the coupling effective, normally ineffective stroke completion means for preventing return movement of the carriage until it has completed its stroke, coin follower means for making the stroke completion means effective in response to a coin on the coin carriage, and a safety stop movable into cooperating engagement with the driven element when the holding pawl is disengaged for limiting the movement of the driven element during disengagement of the holding pawl.

21. Coin controlled mechanism comprising a manually operable driving member, a coin carriage moved in response to rotation of said member, a driven element, driving pawl and ratchet mechanism for coupling said driven element to

the driving member, holding pawl and ratchet mechanism for normally holding the driven element against the movement, trigger means responsive to movement of a coin in the carriage for causing engagement of the driving pawl and disengagement of the holding pawl and thereby making the coupling effective, a trigger lock normally preventing actuation of the trigger, coin follower means for releasing the trigger lock in response to a coin on the coin carriage, and a safety stop movable into cooperating engagement with the driven element when the holding pawl is disengaged for limiting the movement of the driven element during disengagement of the holding pawl.

22. Coin controlled mechanism comprising a manually operable driving member, a coin carriage moved in response to rotation of said member, a driven element, driving pawl and ratchet mechanism for coupling said driven element to the driving member, holding pawl and ratchet mechanism for normally holding the driven element against the movement, trigger means responsive to movement of a coin in the carriage for causing engagement of the driving pawl and disengagement of the holding pawl and thereby making the coupling effective, a trigger lock normally preventing actuation of the trigger, normally ineffective stroke completion means for preventing return movement of the carriage until it has completed its stroke, coin follower means for releasing the trigger lock and for making the stroke completion means effective in response to a coin on the coin carriage, and a safety stop movable into cooperating engagement with the driven element when the holding pawl is disengaged for limiting the movement of the driven element during one disengagement of the holding pawl.
